UNITED STATES PATENT OFFICE.

JOHN F. O'CONNOR, OF CHICAGO, ILLINOIS, ASSIGNOR TO W. H. MINER COMPANY, OF CHICAGO, ILLINOIS, A CORPORATION OF ILLINOIS.

DRAFT-RIGGING.

No. 914,176.

Specification of Letters Patent.

Patented March 2, 1909.

Application filed May 1, 1908. Serial No. 430,261.

To all whom it may concern:

Be it known that I, JOHN F. O'CONNOR, a citizen of the United States, residing in Chicago, in the county of Cook and State of Illinois, have invented a new and useful Improvement in Draft-Rigging, of which the following is a specification.

My invention relates to draft rigging for railway cars.

10 The object of my invention is to provide a draft rigging of a strong, simple, efficient and durable construction, and which will be adapted for use upon single center sill cars without the necessity of cutting or weakening the center sill.

My invention, consists, in connection with a single center sill car, of a stationary draft lug or stop member secured to the center sill below the same, and movable draft members, followers and cushioning devices also mounted below the center sill, transfer levers pivotally connected to said fulcrum plates or members, one on each side of the center sill, and connected at their lower ends to the 25 movable draft members, and a pair of upper movable draft members connected to the draw head and fitting one on each side of the center sill and connected to the upper ends of the transfer levers.

30 My invention further consists in the novel construction of parts and devices and in the novel combinations of parts and devices herein shown and described.

In the accompanying drawing, forming 35 a part of this specification, Figure 1 is a side elevation, partly in vertical section, of a single center sill car draft rigging embodying my invention; Fig. 2 is a plan view, partly in horizontal section; Fig. 3 is a vertical cross section on line 3—3 of Fig. 1; and Fig. 4 is a vertical cross section on line 4—4 of Fig. 1; Fig. 5 is a detail longitudinal sectional view of the frictional cushioning devices.

45 In the drawing A represents the center sill of a car of the kind having a single center sill, A¹ the front or end sill and A² the carry iron.

B is the draw head of the car coupler and B¹ is a pair of upper draft members pivotally connected thereto at their front ends by upright pivot pins b and fitting one on each side of the single center sill A.

C C are a pair of fulcrum plates, rigidly and firmly secured to the single center sill A,

one on each side thereof by rivets c. To 55 these fulcrum plates a pair of upright transfer levers D are pivotally connected by horizontal pivot pins d. The fulcrum plates C have sockets or upright slots c' to receive the transfer levers D. The upper pair of 60 draft members B¹ are pivotally connected at their rear ends to the upper ends of the transfer levers D by horizontal pivot pins d'.

F F are the lower pair of movable draft members, one fitting on each side of the 65 draft rigging cushioning devices and each preferably of a semi-cylindric shape on their inner faces or sides to embrace the cushioning devices, the same being pivotally connected by horizontal pivot pins d' with the 70 upright transfer levers D. Each of the lower movable draft members F is furnished with a pocket or shouldered recess f to embrace and engage the ends of the followers E. The draft rigging cushioning devices pref- 75 erably consist of a spring or springs G g, a longitudinally movable friction shell H, friction blocks H¹, and wedge or spreader block H² in the friction shell H and interposed between the spring G and the front fol- 80 lower E. A preliminary compression block or follower E² is preferably interposed between the rear follower E and the rear end of the spring G.

K is the stationary draft lug or stop member rigidly and firmly secured to the single center sill A, preferably by rivets K¹ extending through the lower flange a of the center sill A, and through the flanges K² of the stop member K. The stop member K is fur- 90 nished with stops or shoulders K³ K⁴ engaging the followers E. The movable draft members F have shoulders f¹ f² which serve for limiting the movement of the followers and the compression of the springs. The 95 central draft lug or stop member K is also provided with a bottom web K⁷ to receive and support the lower pair of movable draft members F F and the cushioning devices embraced thereby. The draft members F 100 have sufficient play between the bottom web or guide K⁷ upon which the same rest and the lower flange a to accommodate the slight swinging movement of the lower ends of the transfer levers D, it being understood in this 105 connection that the total movement of the draw-bar and of the draft members F is ordinarily only about three inches.

I claim:

1. In a single center sill car draft rigging, the combination with the single center sill and draw head, of a draft lug member secured to said center sill below the same and furnished with stops for the followers to abut against, a pair of fulcrum plates secured to said center sill, one on each side thereof, a pair of transfer levers pivotally connected to said fulcrum plates, a pair of movable draft members, one on each side of the plate, and connecting the draw head with the upper ends of said transfer levers, a lower pair of movable draft members connected to the lower ends of said transfer plates and furnished with means for engaging the followers at their ends, and followers and cushioning devices, substantially as specified. 5
2. In a single center sill car draft rigging, the combination with followers and cushioning devices below the center sill, a pair of movable draft members fitting astride the center sill, and connecting means between said movable draft members and the cushioning devices below the center sill, substantially as specified. 10
3. In a single center sill car, the combination with center sill and draw head, of movable draft members fitting astride the center sill, a draft lug member below the center sill, movable draft members below the center sill fitting astride said draft lug member, and connecting means between the upper and lower movable draft members, substantially as specified. 15
4. In a single center sill draft rigging, the combination with cushioning devices, followers, stops and a draft member below the center sill, of a draw head and a pair of movable draft members above the cushioning devices and fitting astride the center sill, and connecting means between said first mentioned and last mentioned movable draft members, substantially as specified. 40
5. In a single center sill draft rigging, the combination with the center sill, of fulcrum plates secured thereto, transfer levers, a draw head and connections between the draw head and said transfer levers, said connections fitting astride the center sill, substantially as specified. 45
6. The combination with a center sill, of a draft lug or stop member secured thereto below the same, provided with stops and a lower web for the draft appliances to rest upon, a pair of movable draft members fitting astride said top member, substantially as specified. 50
7. The combination with a center sill, of draft mechanism below the center sill, a draw head and movable draft members connected to the draw head and fitting one on each side of the center sill and having a pivotal connection with the draw head, and a pair of connecting levers between said draft members and said draft mechanism below the center sill, substantially as specified. 55
